LOCK MECHANISM.

1,218,065.

Specification of Letters Patent.

Patented Mar. 6, 1917.

Application filed October 11, 1915. Serial No. 55,141.

To all whom it may concern:

Be it known that I, WILLIAM F. DIESEL,
of Rochester, in the county of Monroe and
State of New York, have invented certain
5. new and useful Improvements in Lock
Mechanisms; and I do hereby declare the
following to be a full, clear, and exact de-
scription of the same, reference being had
to the accompanying drawings, forming a
10 part of this specification, and to the refer-
ence-numerals marked thereon.

My invention has for its chief purpose to provide a construction characterized by its extreme simplicity and compact arrangement of parts and capable of use in various relations where a lock mechanism may be required. The parts are constructed and assembled in such a way as to insure considerable strength and durability, and the device as a whole is susceptible of ready attachment to a door, or casing, or otherwise, for use in connection with the bolt of a lock. A further advantage of the invention is to be found in its efficiency, as determined by the improbability of the parts becoming in any way disarranged and the difficulties in the way of the lock being picked or accidentally opened. A further object of the improvement is to afford a novel construction involving various detail features in tumbler lock constructions. To these and other ends the invention consists in certain improvements and combinations of parts, all as will be hereinafter more fully described, the novel features being pointed out in the claims at the end of the specification.

In the drawings:

Figure 1 is a horizontal sectional view showing the application of my invention according to a preferred embodiment;

Fig. 2 is a vertical sectional view on line 2^a—2^a of Fig. 1;

Fig. 3 is a sectional view on line 3^a—3^a of Fig. 2;

45 Fig. 4 is a similar view showing the position of the parts after the tumblers and the barrel have been operated, and

Fig. 5 is a view illustrating in elevation the several tumblers employed.

50 Similar reference characters throughout the several views indicate the same parts.

The invention may be carried out and adapted in a number of different ways, without departing from its essential characteristics, and in the present application I have shown its use in connection with a structure that includes a casing 1 and a lock bolt 2 that is movable within the casing into and out of locking position. The structure which constitutes the present improvement is illustrated in controlling relation with the bolt 2 whereby the latter can not be moved from its locking position except when the lock mechanism which I am about to describe is released.

The structure comprises in its general aspect a stationary housing within which is arranged a rotary barrel, the movement of which controls the position of the bolt 2. The barrel referred to carries a plurality of locking tumblers which normally retain the barrel in locked relation with the housing, and are movable to release the barrel upon the insertion of a properly formed key that cooperates with the different tumblers whereupon the barrel may be rotated to operate the bolt. 70 75

With these general purposes in view, the structure embodies a housing 3 provided with openings 4 and 5 at the top and bottom, and held in place in the door or other support 6 by means of threaded bolts 7 which engage correspondingly threaded openings 8 of the housing. 9 is a barrel which is rotatively arranged within the housing and provided with openings 10 normally disposed in coincidence with the openings 4 in the housing as shown in Fig. 3. The

1 in the housing as shown in Fig. 3. The barrel 9 also carries an axially arranged post 11 provided with an opening to receive a key 12, and arranged on the post 11 is a plurality or series of tumblers 13 each having a guiding opening 14 coöperating with the post 11, and end portions 15 adapted to engage the openings 4 and 5 in the barrel and openings 10 of the housing. Thus it will be observed that each tumbler 13 is provided with two locking or end portions 15, one of which is engaged with the housing 3 when in normal locked relation while the other portion 15 is disengaged. To release the lock and permit the barrel to be

turned, each tumbler must be moved to the position indicated in Fig. 4 in which both end portions are disengaged from the housing 3, and if an improper key is employed or improper means are utilized to open the lock, one or more of the tumblers are likely to be withdrawn too far from the housing 3, so that while the portion 15 that normally locks the barrel may be brought into unlocked relation with the housing 3, the opposite end portion of the barrel will be moved far enough to engage the housing 3 and prevent turning of the barrel. This double locking characteristic of the tumblers is a greater insurance against unauthorized opening of the lock, because if any one tumbler is moved slightly beyond its predetermined position for unlocking it will act to maintain the barrel against movement. The tumblers 15 are normally maintained in locking relation with the housing 3, that is with one end engaged with the opening 4, as appears in Fig. 3, by means of springs 17, one of which is attached to each tumbler and engages a shoulder 16 on the barrel, acting to elevate the tumbler to the position shown in Fig. 3. Each tumbler is provided with a cam surface 18 formed differently in the respective tumblers, and the key 12 carries a series of grooves or serrations that afford shoulders for proper coöperation with the cam surfaces on the tumblers, so that when the key is fully inserted and turned, it causes the tumblers to move radially of the barrel until their upper ends are withdrawn from the opening 4, and thereby disengaged from the housing. Continued turning of the key rotates the barrel, and with it a controlling member 18 which is preferably carried by the barrel and operatively connected to the bolt 2.

The invention is not to be limited to any of the features or the precise arrangement herein shown and described, as it is intended to cover any modifications or departures that may come within the spirit of my improvement, and the scope of the claims here-to appended.

I claim as my invention:

50. 1. A lock mechanism comprising a housing having an opening therein, a barrel arranged in the housing and provided with an opening normally in coincidence with the opening in the housing, an axially disposed post in the barrel, a plurality of tumblers having guiding openings coöperating with said post and slideable thereon radially of the barrel into and out of engagement with the opening in the housing, springs engaging the tumblers and acting to retain them normally in locked relation with the housing, and cam surfaces on the tumblers adapted to be engaged by a key to effect sliding of the tum-

blers, and a controlling member carried by the barrel.

65

2. A lock mechanism comprising a housing, a barrel rotatively arranged in the housing, a plurality of tumblers normally holding the housing and barrel in locked relation and movable to release the barrel and permit it to rotate, and cam surfaces disposed on the tumblers at varying distances from the center of the barrel adapted to be engaged by a key to effect sliding of the tumblers and springs acting to return the tumblers to normal position.

70

3. A lock mechanism comprising a housing, a barrel rotatively arranged in the housing, an axially disposed post in the barrel, a plurality of tumblers having guiding openings coöperating with said post and slideable thereon radially of the barrel, springs engaging the tumblers and acting to retain them normally in locked relation with the housing, and cam disposed surfaces on the tumblers at varying distances from the center of the barrel and arranged to be engaged by a key inserted in said post, when the latter is rotated.

80

4. A lock mechanism comprising a housing having an opening therein, a barrel arranged in the housing and provided with an opening normally in coincidence with the opening in the housing, a plurality of tumblers slideable radially of the barrel into and out of engagement with the opening in the housing, springs engaging the tumblers and acting to retain them normally in locked relation with the housing, and cam surfaces disposed on the tumblers at varying distances from the center of the barrel and arranged to be engaged by a key inserted in said post, when the latter is rotated.

90

5. A lock mechanism comprising a housing having oppositely disposed openings therein, a barrel arranged in the housing and provided with openings normally in coincidence with the openings in the housing, an axially disposed post in the barrel, a plurality of tumblers having guiding openings coöperating with said post and slideable thereon radially of the barrel into and out of engagement with the openings in the housing, springs engaging the tumblers and acting to retain them in locked relation with the housing, cam surfaces on the tumblers disposed at varying distances from the center of the barrel and adapted to be engaged by a key to effect sliding of the tumblers, and a controlling member carried by the barrel.

105

6. A lock mechanism comprising a housing having an opening therein, a barrel arranged in the housing and provided with an opening normally in coincidence with

110

115

125

the opening in the housing, a plurality of tumblers slideable radially of the barrel and having cam surfaces disposed at varying distances from the center of the barrel, springs engaging the tumblers and acting to retain them normally in locked relation with the housing, and operating means co-

operating with said cam surfaces on the tumblers.
